CLAIM

The ornamental design for a wall support for bathroom accessories, as shown and described.

DESCRIPTION

FIG. 1 is a top, front, and left side perspective view of a wall support for bathroom accessories showing my new design;

FIG. 2 is a vertical cross-sectional view thereof, taken
through the center of the support from front to rear;

FIG. 3 is a top plan view thereof;

FIG. 4 is a front elevational view thereof;

FIG. 5 is a right side elevational view thereof, the left side being a mirror image of that shown; and,

FIGS. 6 and 7 are top, front, and left side perspective
views thereof, with the broken-line disclosure of bathroom accessories being for illustrative purposes only
and forming no part of the claimed design.
